UNITED STATES PATENT OFFICE.

JOHN HAYS HAMMOND, JR., OF GLOUCESTER, MASSACHUSETTS.

SYSTEM OF ACOUSTIC SIGNALING

1,320,686.

Specification of Letters Patent. Patented Nov. 4, 1919.

Application filed June 10, 1912, Serial No. 702,728. Renewed March 18, 1919. Serial No. 283,444.

To all whom it may concern:

Be it known that I, JOHN HAYS HAMMOND, Jr., a citizen of the United States, residing at Gloucester, in the State of Massachusetts, have invented certain new and useful Improvements in Systems of Acoustic Signaling, of which the following is a specification.

My invention relates to systems of telegraphing, either with or without wires, so as to produce audible or visible signals at the receiving end, and relates more particularly to systems for transmitting signals of varying characteristics, such as pitch and intensity, and receiving them so that they will produce characteristic tones or visible characters. These audible or visible characters will form a telegraphic shorthand system.

In the particular embodiment of my invention here shown I employ acoustic tones of varying pitch to represent characters, and so provide a simple system of high-speed telegraphy.

Referring to the accompanying drawings:—

Figure 1 shows my acoustic telegraph system with an alternating current generator.

Fig. 2 shows my acoustic telegraph system with a variable-pitch buzzer.

Fig. 3 shows my acoustic telegraph system with a telephone transmitter and a variable-pitch buzzer, as applied to present day telephone systems.

Fig. 4 shows my system of acoustic signaling adapted to wireless telephone transmitting and receiving stations.

Fig. 5 shows my system of acoustic signaling adapted to a wireless transmitting station using an electric arc as an oscillatory current generator.

Fig. 6 shows a number of different characters such as can be used with my system.

If I desire to telegraph shorthand characters by the use of acoustic tones of varying pitch, I take a transmitter capable of producing tones ranging in frequency, say, from 200 to 500 per second, and capable of changing the frequency within these limits as quickly or as slowly as may be desired. Then if a character such as that shown at a,

Fig. 6, is to be sent, the transmitting apparatus must be started at the frequency of 200 per second, made to rise to 500 per second as quickly as possible, and then cut off. At the receiving end the signal will then be heard as a sound of rapidly increasing pitch from 200 to 500 periods per second, and may be graphically recorded by the operator as the character shown at a. The distance between the horizontal lines 1, 1 and 2, 2 will represent the interval between the tone of 200 periods per second and the tone of 500 periods.

If a character such as that shown at b, Fig. 6, is to be sent, the transmitting apparatus is started at a frequency of 200 per second, quickly raised to about 350 per second and then cut off. For character c, the transmitter is started at 200 per second, slowly raised to 500 per second, held there for a short time, and then cut off. For character d, the transmitter is started at 200 per second, raised slowly at first and then faster and faster until a frequency of 500 per second is reached, when it is cut off. The rest of the characters shown in Fig. 6, as well as any number of others can be sent and received by my system. The difference in pitch or in intensity, corresponding to the distance between the horizontal lines 1, 1 and 2, 2, can be made anything that is convenient.

In Fig. 1, an alternating current generator G is mechanically connected to an electric motor M, the speed of which is controlled by a variable resistance I connected in circuit with a battery B. A movable switch arm J, in which is a key K, travels over the variable resistance I, and when the key K is closed the circuit through the motor M is completed and the generator G is started. The generator G is inductively connected with the line wires F and F¹ by means of the step-up transformer D D¹, and the line wires lead to a receiving telephone R. When key K is closed and switch arm J is moved over resistance I, the speed of motor M is made to change, and therefore the frequency of generator G is varied, and alternating currents are sent over the line F F¹ producing

an acoustic tone in receiving telephone R, the pitch of which tone is dependent upon the position of switch arm J.

In Fig. 2, a variable-pitch buzzer is used 5 to produce the alternating currents for exciting the receiving telephone. An electromagnet N is connected in circuit with a battery B¹, the primary D² of step-up transformer D² D³, and contact X. An armature 10 N¹ is attached to a wire W which is fixed at Q and P in such a way that when the thumb-screw S is turned the tension of wire W is varied, and its rate of vibration is changed. The contact at X with the block 15 supporting the thumb-screw S is normally disengaged by the action of the compression spring Y, and the end support P of the wire is prevented from rising too far by the stop Z. By pressing the thumb-screw S and end 20 support P downward so as to make contact at X, the buzzer circuit will be closed and the armature N¹ will be attracted by electromagnet N, thus breaking the circuit, which will be immediately closed again, and this 25 making and breaking of the circuit will proceed at a rate depending upon the rate of vibration of the wire W, which vibration rate is dependent upon the tension of the wire. These current changes in primary D² will in- 30 duce corresponding changes in secondary D³ and hence in the line F² F³ and receiving telephone R¹. By turning the screw S, the rate of vibration of the wire W is changed and corresponding acoustic tones are heard 35 at receiving telephone R¹.

In Fig. 3, V is a variable-pitch buzzer energized by battery B² and controlled by thumb-screw S¹, said buzzer impressing sound waves on telephone transmitter T, 40 which is in circuit with battery B³ and primary D⁴ of induction coil D⁴ D⁵, the secondary D⁵ being in circuit with line F⁴ F⁵ and receiving telephone R². By varying the adjustment of buzzer V, tones of varying pitch, 45 corresponding to different characters, are sent over the line to the receiver R².

In Fig. 4, a high-frequency alternator H energizes antenna A through coupling coils L and L¹. Antenna A is connected in any 50 suitable way with the microphone transmitter T¹ and is grounded at E. A variable-pitch buzzer V¹ is energized by battery B⁴ and controlled by thumb-screw S², and said buzzer impresses sound waves upon micro- 55 phones T¹, thus impressing amplitude variations upon the electric waves radiated from antenna A. The receiving antenna A¹ is in circuit with the tuning coil L² and the variable condenser C, and is grounded at E¹. 60 Said antenna is inductively coupled to the closed oscillatory circuit L³ C¹, consisting of coil L³ and condenser C¹, which circuit supplies unidirectional currents to receiving

telephone R³ by the action of the rectifier r. The antenna circuit A¹ L² C E¹ and the 65 closed oscillatory circuit L³ C¹ are both tuned to the frequency of the alternator H, and when sound waves are produced at buzzer V¹, they will be reproduced at the receiving telephone R³. 70

In Fig. 5, an oscillatory arc O is supplied from a source of direct current B⁵ through the choking coils U and U¹. An oscillatory circuit, containing the condenser C² and the inductance coil L⁴, is shunted around the arc 75 and is inductively coupled to the antenna A² by means of the coil L⁵. The values of capacity C² and inductance L⁴ are such that high-frequency oscillatory currents will be produced in the circuit, such that electric 80 waves of a suitable frequency will be radiated from A². Around the arc O there is also shunted another oscillatory circuit containing the variable condenser C³, the key K¹ and the coil L⁶. Capacity C³ and in- 85 ductance L⁶ have such values that in their circuit there will be produced oscillatory currents of frequencies within the limits of audibility. When the key K¹ is closed and the value of capacity C³ is varied amplitude 90 variation corresponding to audible tones will be impressed upon the waves radiated from antenna A². A receiving apparatus similar to that of Fig. 4 can be used with this transmitting apparatus, and as the ca- 95 pacity C³ is varied, correspondingly varying acoustic tones will be heard in the receiving telephone.

I claim as my invention:—

1. A method of electric signaling in 100 which characters are indicated by acoustic tones, which consists in changing the pitch with respect to a predetermined note at different rates of speed to indicate the form of the characters to be reproduced.

2. A method of electric signaling in which characters are indicated by acoustic tones which consists in changing the pitch at a varying rate to indicate a curvilinear character. 105

3. A method of electric wave signaling in which characters are indicated by acoustic tones, which consists in changing the pitch with respect to a predetermined note at different rates of speed to indicate the form of the characters to be reproduced. 110

4. A method of electric wave signaling in which characters are indicated by acoustic tones which consists in changing the pitch at a varying rate to indicate a curvi- 115 linear character.

5. A code for signaling by sound waves in which various characters are indicated respectively by predetermined relative changes in the pitch of acoustic tones and 120 in the rate of change of said pitch. 125

6. A code for signaling by sound waves in which various characters are indicated respectively by transmitting acoustic tones and varying the pitch of said tones at various predetermined rates.
7. A code for signaling by sound waves in which various predetermined characters are indicated respectively by predetermined changes in the pitch of acoustic tones and
- by predetermined variations in the rates of 10 effecting said changes.
- This specification signed and witnessed this 22nd day of May A. D. 1912.

JOHN HAYS HAMMOND, JR.
